UNITED STATES PATENT OFFICE

2,105,711

METHOD FOR PRODUCING LAYERS OF DISTENDED FIBROUS MATERIAL

George C. Weathered, Chicago, Ill., assignor to
Cellufoam Corporation, Chicago, Ill., a corporation of Delaware

Application January 22, 1936, Serial No. 60,215

3 Claims. (Cl. 92—39)

The method hereinafter described relates to the production of layers of distended fibrous material of the character set forth in the Bryant Patent No. 1,740,280, issued December 17, 1929. The product therein described is made from cellulose fibers which, mixed with a high percentage of water in the form of a thin mix, are treated with a foaming agent, particularly saponin, and agitated, which results in the production of a foamy mass which after drying maintains the form of a loose or fluffy mass of fibrous materials adapted for numerous uses, particularly for insulating, hospital use, sanitary bandages, and the like.

In the production of such material, it is customary to prepare a thin mix, and after the same has been foamed by agitation to the desired extent to discharge a layer thereof onto the moving wire of a Fourdrinier machine, whereon the same is subjected to suction to remove a portion of the liquid and thereafter fed through a drier, from which the material emerges in the form of a relatively thick and coherent layer of light fluffy distended fibrous material having a surface skin formed thereon by compacting of the surface fibers under suction, in which form the layer is cut to the desired lengths and used for the intended purpose. The steps involved in the production of such layers are set forth and described in the Bryant Patent No. 1,841,785, issued January 19, 1932; the Bryant Patent No. 1,870,279, issued August 9, 1932; and the Bryant Patent No. 1,929,090, issued October 3, 1933.

In the general method involved in the production of distended fibrous layers as set forth in the foregoing patents, difficulty in commercial production has heretofore been experienced in maintaining uniformity in the thickness and density of the layer by reason of the fact that heretofore means were not provided to definitely regulate the quantities of fiber and saponin and water fed into the mix or to precisely control the discharge of the mix onto the wire of the Fourdrinier machine, and the present invention is directed to a method for overcoming the difficulties above mentioned and for securing greater uniformity in the thickness and character of the resulting product under conditions permitting rapid production of the material by a continuous operation.

The present invention, therefore, is directed to the method provided for rapidly and uniformly feeding the fibrous material in relatively small particles or masses; to the measuring of the fibrous material and the liquid mixing agents employed; to the steps provided for insuring a complete and uniform mixture of the constituent ma-

terials prior to the discharge, and to the regulating of the discharge of the mix onto the wire of the Fourdrinier machine in the form of a layer of uniform thickness and homogeneous character.

Further objects and details of the invention will appear from a description of the same in conjunction with the accompanying drawings, wherein,—

Figure 1 is a diagrammatic plan view of the ground floor portion of the apparatus employed in the present invention;

Fig. 2 is an enlarged side elevation of the mixing tanks, the mechanism employed for measuring the mix, the agitating tank, and the wet end of a Fourdrinier machine;

Fig. 3 is a sectional elevation of the mixing tanks, the measuring valve, and the agitating tank;

Fig. 4 is an end view of the agitating tank with the discharge gate as viewed from line 4 of Fig. 3;

Fig. 5 is a perspective view of one of the rotary stirrers or paddles;

Fig. 6 is an enlarged cross sectional view of the measuring valve for measuring off charges of the mix;

Fig. 7 is a longitudinal section of the same on line 7; and

Fig. 8 is an enlarged detail of the ratchet mechanism for controlling the rotation of the measuring valve.

Referring first to the general method involved, as illustrated in Fig. 1, the fibrous material is first of all subjected to a beating operation in a beater tank 20, which is provided with a circuitous channel 21 afforded by an outer continuous wall 22 and an inner continuous wall 23. Across the channel thus formed extends a beater roll 24 which is rotated by a pulley 25 and a belt 26 leading to a motor 27.

The fibrous material, in the form of a thin slurry, containing about 5% fiber and 95% water, is acted upon in the beater for a period of time which may vary from thirty minutes to two hours or more, depending upon the extent to which it is desired to hydrate and gelatinize the fibers, but for most purposes the beating operation will continue for about an hour, in accordance with the principles set forth and described in the Bryant Patent No. 1,841,785, previously mentioned.

The mix is withdrawn from the beater through a pipe 28 leading to a pump 29, which thereafter elevates the pulp through a pipe 30 to a head tank 31, within which is located a stirrer or paddle provided for the purpose of maintaining the mix in a homogeneous condition.

The mix is fed down from the head tank to an expeller 32, through which the pulp is fed and a predetermined portion of the water expelled by compression in a manner well understood in the art. From the expeller the partially dried pulp is fed outwardly and caught in a pail 33 carried by a truck 34. The pulp at this stage has a known water content which is important in the securing of uniformity in the mix procured as the result 10 of subsequent operations.

The mechanisms heretofore described are of standard construction and of a character commonly employed in the paper making or other allied arts, so that a detailed description of each of 15 said mechanisms is not required.

The charge of material in the pail 33 is elevated by a cable 35 to an upper elevation in the building, wherein are located a pair of mixing tanks 36, which are duplicates, each of which is 20 provided with a discharge pipe 37 leading to a common discharge pipe 38. The arrangement is one which enables the operator to employ the mixing tanks alternately by making up a mix of material in one of the tanks while the other is 25 discharging, so that a continuous flow of properly mixed material can be constantly maintained.

Since the tanks are duplicates of one another, 30 description of one will suffice for both. Each tank has a conical hopper bottom 39 leading to the inlet end of the discharge pipe 37, which is controlled by means of a plug valve 40 at the lower end of a valve stem 41, which stem at its upper end is provided with screw threads 42 entered through a bushing 43 depending from a bridge plate 44. The valve stem is provided at its upper end with a handle 45, which permits the valve stem to be raised and lowered to seat or unseat the plug valve 40 as occasion may require.

The valve stem 41 is surrounded by a tubular shaft 46 which is carried by the hub 47 of a bevel gear 48. The tubular shaft is journalled through a journal block 49 in the center of a bridge plate 45 or spider 50 which spans the upper rim of the tank.

The tubular shaft is provided with paddles or beater bars 51, and the outer end of the lowermost beater bar 52 is upturned to lie in closely 50 adjacent relation to the conical hopper bottom and serve as a scraper bar for preventing the material from adhering to the walls of the tank.

The fibrous material is discharged from the pail into the tank which is under replenishment 55 for the time being, and as the properly measured quantity of material is being poured into the tank, a liquid solution which consists mainly of water with a charge of saponin supplied thereto as a foaming agent is discharged through a pipe 53, each of the tanks being supplied with one of such pipes, which unite in a three-way valve casing 54 and connect with a header pipe 55 leading to a meter 56 having a supply pipe 57, through which the solution of water and saponin is admitted in measured quantities to unite with a measured quantity of fibrous material of known liquid content, so that by properly measuring out the amounts of fibrous material and saponin solution, a mix of predetermined liquid content 60 will be admitted to the tank and subjected to a mixing or stirring action throughout the period of time required for the discharge of previously mixed material from the companion tank, with the result that a proper mix will be maintained 70 at all times, which is highly essential in securing

uniformity in the density and thickness of the completed layer of distended fibrous material.

The mix, after being discharged through one of the pipes 37 and through the common discharge pipe 38, enters a cylindrical measuring 5 valve casing 58, within which is located a shaft 59 carrying radially extending wings or plates 60, four being shown in the present embodiment. Adjoining plates are united by a curving outer wall 61 which lies in closely adjacent relation 10 to the surrounding wall of the casing, so that a pair of radial wings or plates 60 with the connecting curving wall 61 constitute in effect a segment, and between the two segments thus formed are located open cavities 62 which constitute the 15 pockets for the reception of charges of the mix, which by rotation of the shaft 59 are carried around to the lower side of the valve chamber and discharged through a discharge pipe 63 located above the first compartment of an agitator tank 64 presently to be described.

The ends of the pockets 62 in the measuring valve member are closed by head walls 65 which rotate within recesses 66 in head plates 67 constituting part of the valve casing, and in order to afford a sharp cutting edge for shearing the fibrous material, the leading wing or plate of each segment pair is provided with a cutting blade 68 which coats with a cutting blade 69 located at the shoulder formed by the emergence of the 25 throat 70 into the interior cylindrical wall of the valve casing. The arrangement is one which affords a shearing action for insuring a sharp severance of the material and for preventing leakage between the wall of the casing and the rotating measuring valve located therein.

The shearing knife blades 68 and 69 extend from end to end of the rotating valve, and the throat 70 likewise extends from end to end of the valve casing, with the pipe 38 centrally located 40 to discharge into the chamber thus afforded in the throat, which permits the liquid and fiber mix to distribute itself equally from end to end of the casing and to flow down into whichever of the measuring pockets is moving through the upper portion of its rotation for the time being. In order to allow air to be vented as the mix flows into the pocket, a vent plug 71 is provided at a point closely adjacent the throat 70, so that, as the measuring valve rotates and the material is delivered into the upwardly presented pocket, the air will be ejected, permitting the pocket to fill up to the top, without cavities or open interstices therein, so that, when the charge is cut off by the shearing action of the knife blades, a 50 measured charge of predetermined amount will be carried downwardly to the discharging position.

The measuring valve is rotated by the mechanism shown in Fig. 8. This consists of a ratchet 66 wheel 72 keyed upon the shaft 59, which ratchet wheel cooperates with a dog 73 carried between an outer lever arm 74 and an inner arm 75 connected by the shoulder 76 with the lever arm. The arms 74 and 75 are pivoted upon shouldered hubs 77 freely mounted upon the shaft 59, each of the hubs being provided with an arm 77a, which arms in unison are pivoted to the outer ends of links 78, the inner ends of which straddle an adjusting screw block 79 on an adjusting 70 screw 80 journalled through a standard 81 and operable by a hand wheel 82. The links 78 cooperate with lower links 83 pivoted upon the lug 84.

The arms 77 support between them an arcuate shield 85 which overlies the teeth on the 76

ratchet 72 and is adapted to be adjusted there-over to disable the action of the dog 73 to the desired degree. In Fig. 8, the position assumed by the arm 74 at the end of its thrust to the right is indicated in dotted lines, from which it will be observed that the shield 85 in the position shown serves to cut off four of the teeth, and to that extent reduces the range of movement of the measuring valve upon each operation of the ratchet. The arm 74 is actuated by a link 86 (Fig. 2) which connects with a rocking arm 87 actuated by a star wheel 88, which in turn is rotated by worm gearing 89 driven by a motor 90. Any other suitable mechanism for imparting oscillations to the arm 74 might be employed, but by adjusting the effective range of action of the dog 73 in the manner shown, it is possible to closely regulate the feeding speed of the measuring valve so that the material will be delivered to the tank 64 in uniform relation to its discharge onto the wire of the Fourdrinier machine.

The tank 64 in the form shown consists of an upper section 91 and a lower section 92, arranged in superposed relation and connected through a duct 93. This arrangement is desirable in that it conserves floor space, although the same result would be obtained by an arrangement in which the two sections were aligned with one another or merged into a single tank of corresponding length.

In Fig. 3, the center portions of the tank sections are broken away, but as indicated in Fig. 2, the lower tank section comprises ten compartments, and the upper section four compartments, which are separated from one another by weirs 94, which as shown are of progressively reduced height from the intake end toward the discharge end of each tank section. Each of the compartments thus formed is provided with a group of stirrers, each in the form of upper and lower paddles 95 and 96 mounted upon a vertical shaft 97. The upper and lower paddles stand in vertically spaced relation to one another, the spacing being greater in the deeper compartments and correspondingly less as the depth of the compartments decreases toward the discharge end of the tank section. The lowermost paddles, however, stand at a uniform height above the floor of the tank.

The four shafts for actuating a single group of stirrers stand vertically in parallel aligned relation from side to side of the tank compartment within which they are located, and the shafts are journaled through bridge bars 98, and are also provided with pulleys 99 and belts 100 so arranged that all of the shafts will be operated in unison. As shown in Fig. 1, power is imparted to the outermost shafts at one end of adjoining groups through power belts 101 operated by a driving pulley 102, which drives the outermost shafts of adjoining groups, and the power thus imparted is distributed to the next adjacent shafts of a group through transmission belts, and from pulley to pulley throughout the members of each group in like manner.

At the right lower portion of Fig. 1 an alternate method of driving is shown, in which the driving pulley 102 imparts power to adjacent groups through belts 103. The particular method of driving, however, is immaterial so long as provision is made for the uniform rotation of all of the stirrers in unison from a common source of power.

Each of the paddles is provided with blades

104 which extend outwardly and terminate in rearwardly extending downturned wings 105, the arrangement being such as to produce a vortical motion within the liquid mix, which tends to draw the material toward the center, although constantly permitting the escape of some of the material over the lower weir and toward the discharge end of the tank.

The mix of materials is discharged from the mixing valve into the bottom of the first compartment in the upper tier. The last compartment in the upper tier on the discharge side is provided with a wall 106 above which is located a flap valve 107 mounted on a shaft 108 operated by a handle through a worm and gear arrangement 109, which enables the flap valve to be elevated to afford the desired clearance above the wall 106.

The duct 93 discharges beneath the lower edge of the wall 106 and into the first compartment of the lower tier. The last compartment of the lower tier is provided with a curving bottom plate 110 which extends from the crest of the last weir downwardly and forwardly and terminates in a lip 111 which contacts the surface of the wire 112 on the Fourdrinier machine, thus furnishing the discharging edge for the outflow of a layer of material.

In order to level down the layer thus discharged, a gate 113 is provided which is of angle formation comprising a flat bottom wall 114, and an upstanding wall 115 which is provided with blocks 116, which receive adjusting screws 117 operated by bevel gearing 118 to raise and lower the gate, in order to provide the desired clearance for the discharge of the layer of material onto the Fourdrinier machine. The gate is provided with an adjustable face plate 119 which permits the clearance to be further regulated.

After the layer of material has been flowed onto the wire of the Fourdrinier machine, it is confined in the form of a straight edged layer between deckle strips 120, and as the wire advances, this layer is subjected to the suction of vacuum boxes 121 and finally delivered across a transfer belt 122 into an oven 123, where it is subjected to a drying process prior to its ultimate delivery and severance into sections of the desired length. These operations are described in the Bryant Patent No. 1,841,785, and need not be here described in complete detail.

The mix thus measured out flows into the first compartment of the upper series and fills the compartment to the level of the weir. The stirrers, being operated in unison throughout the different compartments, will cause rotation of the upper and lower paddles which impart a vortical movement to the liquid inflowing into each of the compartments in turn, and the movement thus imparted tends to draw the liquid mix toward the center of the vortex, but as the liquid rises to the level of the weir, a portion thereof will escape into the next compartment, so that, as the compartments become filled, there will be a constant overflowing of the weirs, at a descending level, however, in each section of the tank, a portion of the liquid escaping over the weir and the remainder being drawn back into the vortex, so that the material in each compartment will be repeatedly recirculated before a portion thereof overflows and escapes, and this operation will continue throughout the upper and lower sections of the tank, thereby thoroughly agitating and foaming the liquid mix and causing a thorough diffusion and distention of the fibrous par-

ticles which are held in distended relation by the minute bubbles composing the foam, so that by the time the mix reaches the point of final discharge onto the wire of the Fourdrinier machine it will be thoroughly agitated and in the condition of a foamy or frothy layer.

By regulating the position of the level of the flap valve 107 and the position of the gate 113, a uniform stream of material may be maintained at the point of discharge and deposited upon the wire of the Fourdrinier machine in the form of a layer of uniform depth and uniform consistency. The layer thus deposited at the wet end of the wire will be confined between the 10 deckle strips and advanced by the Fourdrinier wire, which permits a portion of the liquid to drain away and a portion thereof to be extracted by suction, which also has the effect of forming upon the surface a relatively thin tough paper-like skin, which in the completed product serves to maintain the sections in a relatively stiff and coherent condition, so that they may be ultimately cut to the desired size for the intended use.

25 By the employment of pulp of the desired character, and by regulating the fluidity of the same and the extent of the agitation to which it is subjected and the amount of the foaming agent employed, it is possible, within wide limits, to 30 vary the quality and character of the resulting product, including the degree of distention of the fibrous particles, and the softness or fluffiness of the product. It is thus possible to produce distended fibrous materials of sufficient 35 softness, fineness and distention to serve in hospital use, or for sanitary purposes, or to vary the treatment in such a way as to secure a product of the requisite firmness and stiffness to serve as an insulating layer in buildings, refrigerating 40 appliances, or under like conditions where an insulating layer is required.

Although the method has been described with considerable detail, it is not the intention, unless otherwise indicated in the claims, to limit 45 the claims to the precise method described, since modifications in detail may be introduced without departing from the spirit of the invention.

I claim:

50 1. The method of producing a coherent layer of distended fibrous material of substantially uniform width and thickness, which consists in maintaining contiguous pools of liquid mix having their surfaces at progressively lower levels, supplying measured quantities of fiber and liquid including a foaming agent to the first pool of the 55 series in the amounts required to provide a mix of the desired consistency, constantly maintaining individual agitation in each of the pools to the extent required to cause foaming of the mixture 60 and to separate and maintain the fibers in distended relation within the foamy mass, discharging from each pool by overflow to the sur-

face of the next pool in the form of a broad even layer and discharging from the last pool of the series in the form of a broad even continuously horizontally advancing layer of uniform thickness, confining the sides of the advancing layer 5 to maintain a uniform width for the layer, and extracting liquid from the layer during its advancement to the extent necessary to make the layer self-sustaining and capable of manipulation.

10 2. The method of producing a coherent layer of distended fibrous material of substantially uniform width and thickness, which consists in maintaining contiguous pools of liquid mix having their surfaces at progressively lower levels, supplying automatically measured quantities of fiber and liquid including a foaming agent and commingling the same to provide a mix of the desired consistency, supplying said mix to the first pool 15 of the series and constantly maintaining individual vertical agitation in each of the pools to the extent required to maintain the mix in a foamy condition, and to separate and maintain the fibers in distended relation within the foamy mass, discharging from each pool by overflow to 20 the surface of the next pool in the form of a broad even layer and discharging from the last pool of the series in the form of a broad even continuously horizontally advancing layer of uniform thickness, confining the sides of the advancing 25 layer to maintain a uniform width for the layer, and extracting liquid from the layer during its advancement to the extent necessary to make the layer self-sustaining and capable of manipulation.

3. The method of producing a coherent layer of 30 distended fibrous material of substantially uniform width and thickness, which consists in maintaining contiguous pools of liquid mix having their surfaces at progressively lower levels, providing different sources of supply for measured 35 quantities of fiber and liquid including a foaming agent combined in the amounts required to provide a mix of the desired consistency, delivering charges of said mix alternately from each of said sources to the first pool of the series and constantly maintaining individual vertical agitation 40 in each of the pools to the extent required to cause foaming of the mix and to separate and maintain the fibers in distended relation within the foamy mass, discharging from each pool by overflow to 45 the surface of the next pool in the form of a broad even layer and discharging from the last pool of the series in the form of a broad even continuously horizontally advancing layer of uniform thickness, confining the sides of the advancing 50 layer to maintain a uniform width for the layer, and extracting liquid from the layer during its advancement to the extent necessary to make the layer self-sustaining and capable of manipulation.

60 GEORGE C. WEATHERED.
